UNITED STATES PATENT OFFICE.

ALEXANDER E. DAVISON, OF THE UNITED STATES ARMY.

COLLAR-BUTTON.

1,247,231.

Specification of Letters Patent. Patented Nov. 20, 1917.

Application filed March 17, 1917. Serial No. 155,595.

To all whom it may concern:

Be it known that I, ALEXANDER E. DAVISON, a citizen of the United States, and a sergeant in the Quartermaster Corps of the United States Army, stationed at Gatun, Canal Zone, have invented certain new and useful Improvements in Collar-Buttons, of which the following is a full and exact specification.

- 10 The present invention relates to collar buttons, and aims to provide an improved construction for this class of devices which will facilitate the application and removal of the collar.
- 15 It is also an object to devise a construction and arrangement which will fit snugly in the wearing position with as little tendency as possible to bulge out the garment or collar material or to interfere with the 20 free movement of the tie or cravat past the button.

It is also sought to produce a form of device which, while of neat and effective design, may be readily and economically manufactured from light and durable but inexpensive material.

With this general object in view the invention will now be described with reference to the accompanying drawing illustrating forms of construction which have been devised for embodying the proposed improvements, after which those features deemed to be novel will be set forth and defined in the appended claims.

25 In the drawing—

Figure 1 shows a perspective view of a collar button constructed in accordance with the present invention;

Fig. 2 is a similar view, but showing the 40 collar retaining finger arranged in a different relation;

Fig. 3 is a fragmentary plan view showing a portion of the neckband of a shirt with my type of collar button applied thereto;

Fig. 4 is a fragmentary sectional view, taken on the line IV—IV of Fig. 3, but also illustrating a collar in attached position; and

50 Fig. 5 is a fragmentary plan view illustrating the manner of passing the collar over the collar retaining finger of the device.

Referring to the drawing in detail, this 55 illustrates the device as formed from any

suitable material, such as light sheet metal, from which the button may be conveniently stamped to provide an elongated body portion 2 for attachment to the shirt 4 and adapted to be inserted between the plies of the neckband 6 thereof. From the lower edge of the body portion 2 and intermediate its ends and at right angles thereto projects a shank portion 8 adapted to extend through the usual buttonhole 10 provided in the outer ply of said neckband 6. At the outer end of this shank portion 8 the same is provided with a collar retaining finger 12 which also projects at right angles to said shank and in a lateral or horizontal direction parallel to the main body portion 2 of the device. This retaining finger 12 is of an elongated, and preferably somewhat oval form, with its larger portion located out toward the free end of said retaining finger. It is also deemed expedient to turn or roll one of the side edges of the shank 8 to form a reinforcing bead 14 for said shank portion, which bead is preferably located on the side edge which faces in the direction of the collar retaining finger 12, so that when the buttonhole 18 of the collar 16 is applied to the button (as in Figs. 4 and 5), this bead will provide a smooth abutment for the edge of said buttonhole 80 as well as a smooth and curved engaging surface therefor during the turning of the collar from slightly inclined position (Fig. 5) to horizontal position for slipping the buttonhole 18 on to the shank 8 of the button. The relation of the width of the retaining finger 12 to the usual size of buttonhole 18 will be such as to permit the collar to be slipped over the finger 12 with the collar in slightly inclined position as shown in Fig. 5, and the lower edge of the inner end of the finger 12 is cut away, forming a convex outline and thereby facilitating the shifting of the collar to horizontal position ready to slip over on to the shank 8. 90

It will thus be apparent that a neat, simple and inexpensive construction has been devised for carrying out the desired object's of the invention. The button is applied to the shirt by inserting it between the plies of the neckband and pushing the finger 12 out through the buttonhole 10. The collar 16 may then be applied by simply hooking its buttonhole 18 on to the retaining finger 12, the collar being tilted sufficiently (as indi- 105 110

cated in Fig. 5) to permit its being slipped over said finger until one end of the button-hole 18 is engaged with the bead 14, when the collar may be readily turned to horizontal and slipped on to the shank 8 to embrace the neckband of the shirt. The device will allow very little play of the collar when in wearing position, and the shape and relative position of the retaining finger will 5 obviously act to retain the collar securely in proper place. The collar may be easily and quickly removed by shifting it a trifle backward off the shank 8 and giving the collar a slight pull in the direction of the 10 retaining finger 12. It is of course immaterial in which lateral direction the retaining finger 12 extends, and for the purpose of accommodating the preference of the wearer, said finger may be made to extend 15 either to the right as in Fig. 1 or to the left as shown in Fig. 2. Besides metal, the device is adapted to be made from any light and durable material, such as bone, ivory and the like, and with the thin flat body portion 2 shown it will be apparent that the same will fit snugly between the folds of the neckband 6 and not produce any appreciable hump or bulge at this point, while the thin and flat type of retaining finger 12 20 will offer little or no interference to the movements of the tie when it is desired to shift the latter about the collar. The style of collar 16 shown in the drawing is of course merely illustrative, as it is clear that 25 the device is as well adapted for the folded type of collar. Moreover, the peculiar form of the device will be found to be such as to prevent its rolling away out of sight or reach after the usual fashion of collar buttons, in case they slip out of the grasp of 30 the owner. Finally, the device is of such a simple design of construction as to be manufactured with great facility and economy 35 from very inexpensive materials.

40 45 While the foregoing illustrates what has been found to be a convenient and practical construction for embodying the invention, the right is reserved to such formal changes

or variations as may fairly fall within the scope of the appended claims.

50

What I claim as my invention is:

1. A button for attaching collars to shirts comprising a body portion for insertion between the plies of the neckband of the shirt, a shank portion for projecting through the 55 buttonhole of the neckband, and a collar retaining portion projecting at right angles to said shank and in a direction parallel to said body portion, said retaining portion gradually enlarging toward the free end thereof. 60

2. A collar button formed of flat material and comprising a body or shirt engaging portion, an outwardly projecting shank, and an elongated collar-retaining portion projecting horizontally from the outer end of 65 said shank, said shank being formed with a marginal roll or bead along the side facing in the direction of said collar-retaining portion.

3. A collar button formed of flat ma- 70 terial and comprising a shank portion, an elongated shirt-engaging portion extending upward from one end of said shank and at right angles to the plane of said shank portion and a collar-retaining finger extending 75 downward from the opposite end of said shank at right angles to the plane thereof and projecting laterally therefrom in a direction parallel to said shirt-engaging portion.

4. A collar button formed of flat material and comprising a shank portion, an elongated shirt-engaging portion extending upward from one end of said shank, and a collar-retaining finger extending downward 85 from the opposite end of said shank and projecting laterally therefrom in a direction parallel to said shirt-engaging portion, said shank being formed with a marginal bead along the side facing in the direction of said 90 retaining finger, and the lower edge of the attached end of said finger being of convex outline.

In witness whereof I hereto affix my signature.

ALEXANDER E. DAVISON.
